UNITED STATES PATENT OFFICE

GEORGE WALTHER, OF ROCKVILLE CENTER, NEW YORK.

FINGER-NAIL CLEANER.

1,015,860.

Specification of Letters Patent. Patented Jan. 30, 1912.

Application filed June 2, 1911. Serial No. 630,805.

To all whom it may concern:

Be it known that I, GEORGE WALTHER, a citizen of the United States, residing at Rockville Center, in the county of Nassau and State of New York, have invented certain new and useful Improvements in Finger-Nail Cleaners, of which the following is a specification.

This invention relates to improvements in finger nail polishing machines.

The principal object of the invention is to provide a device of this character which is simple in construction, easy of operation, and by means of which a person may readily clean and polish the nails of both hands.

Other objects and advantages will be apparent as the following description proceeds.

In the drawings: Figure 1 is a side elevation of the device, one side of the cover being removed. Fig. 2 is an end elevation of the same. Fig. 3 is a vertical section on the line 3—3 of the upper portion of the device as shown in Fig. 1. Fig. 4 is a horizontal section on the line 4—4 of Fig. 1. Fig. 5 is an enlarged detailed perspective view of the finger rest. Fig. 6 is an enlarged detailed perspective view of the cleaning and polishing tool and holder.

Referring to the drawings 10 represents the base of the device, which is a box like structure, in which is arranged a drawer 11 to hold the different cleaning and polishing tools and other necessary tools and appurtenances.

Secured to the base 10, on its upper face, by means of the feet 12 is an inverted U-shaped frame member 13, having the perforated ears 14 to receive screws for securing the cover plates 15. There are two of these plates 15, one on each side of the frame.

Mounted in the lower portion of the frame 13 is a platform 16, adjustable vertically by means of the bolts 17 thereon, and the slots 18 in the sides of the frame.

Mounted centrally on the platform 16 is a cylindrical member 19 having mounted to slide vertically therein a rod 20, on the upper end of which is a circular discal head 21, on which a finger of the hand is laid in the operation of cleaning and polishing the nails. In the upper portion of the same is a second platform 22 on which is mounted the parallel vertical supports 23, on the up-

per ends of which are formed the journals 24 for the reception of the horizontally disposed shafts 25. The outer ends of the shafts 25 are journaled in the vertical members of the frame, and on their outer ends, 60 which project beyond the frame are provided with the crank handles 26, by means of which the shafts may be rotated. On the inner end of each of the shafts is a beveled pinion 27 which mesh with the opposite 65 sides of a similar pinion 28 mounted on the upper end of the polishing shaft 29. Disposed across the supports 23, and below the pinion 28 is a platform 30 having an opening therethrough, and a reinforcing plate 70 31 in which is journaled the upper end of the shaft 29. On the lower end of the shaft 29 is a collar 32 for the reception of the cleaning and polishing tools 33, said tools being held in said collar by means of the 75 set screw 34. By means of this set screw 34 and the set screw 19 of the finger rest, the tool and the finger rest, are readily adjustable toward each other to bring the polishing head of the tool 33 into engagement with the nail. The adjustment of the platform 16 makes it possible to further adjust the finger toward the polishing tool.

In the operation of the device, as in cleaning and polishing the nails of the left hand, 85 the finger rest and tool are properly adjusted, with the finger on the finger rest. The handle 26 on the right hand side of the frame is rotated, which through the gears 27 and 28 rotates the polishing tool 33 90 against the finger nail. In cleaning and polishing the nails of the right hand, the operation is the same as just described, except that the crank 26 at the left of the machine is operated.

From the foregoing it will thus be seen that the device is simple in construction and easy of operation, and provides means for adjusting the various parts, and making it easy to clean the nails of the right and left hands.

What is claimed is:

1. A finger nail cleaning and polishing device comprising a base, an inverted U-shaped frame mounted on the base, a platform mounted in the upper portion of the frame, supports on said platform, driving shafts journaled in said supports and in the frame, a driven shaft journaled in said platform, an adjustable finger rest in the lower

portion of the frame, and a cleaning and polishing tool on the lower end of said driven shaft.

2. A finger nail cleaning and polishing device comprising a base, a frame mounted on the base, driving shafts mounted in the frame, cranks for rotating said shafts, a vertically arranged driven shaft, a tool holder in the lower end of said driven shaft, 10 a vertically adjustable platform in the lower

portion of the frame, a finger rest on said platform, and means for adjusting said finger rest independently of the platform.

In testimony whereof I affix my signature, in the presence of two witnesses.

GEORGE WALTHER.
